INVENTOR.

FRANK M. STOLL
BY
P. H. Hallwright
ATTORNEY.

UNITED STATES PATENT OFFICE.

FRANK M. STOLL, OF DENVER, COLORADO.

PORTABLE AND COLLAPSIBLE BED.

Application filed March 21, 1922. Serial No. 545,585.

To all whom it may concern:

Be it known that I, FRANK M. STOLL, a citizen of the United States of America, residing at Denver, in the county of Denver and State of Colorado, have invented certain new and useful Improvements in Portable and Collapsible Beds, of which the following is a specification.

The invention relates to portable and collapsible beds, more particularly of the type used by campers and autoists and has for its principal object the provision of a bed of this character which can be quickly and easily set up or collapsed and in which the 15 spring structure can be stretched taut with a minimum of effort.

Another object of the invention is to reduce the number of parts usually found in beds of this character so as to lighten the 20 bed and reduce the cost of manufacture.

Further objects of the invention reside in the detail construction thereof and in the ways and means of connecting the various detachable parts. These objects will become 25 apparent from the following description.

The invention will now be described with reference to the accompanying drawing which forms a part hereof. Corresponding and like parts are referred to in the description and indicated in all views of the accompanying drawing by the same reference characters.

In the drawing:

Figure 1 is a plan view of the bed with the 35 spring structure partly broken away to show the supporting structure.

Fig. 2 is a side elevation of the complete bed.

Fig. 3 is a detail perspective view showing 40 the manner in which the end members of the bed are detachably engaged with the leg members.

Fig. 4 is a similar view showing the manner in which the cross braces are detachably 45 engaged with the longitudinal members.

Fig. 5 is a plan view of a portion of one 50 of the longitudinal members showing the position of the spring structure tightening mechanism before the tightening operation.

Fig. 6 is a similar view after the tightening operation.

Fig. 7 is a side elevation of the device as shown in Fig. 6.

Fig. 8 is a side view of one of the longitudinal members with its attached leg and

cross members in the folded or collapsed position.

Let the numeral 10 designate a spring structure of the usual construction, having a series of longitudinal flexible members 11 60 terminating in springs 12. Spring structure 10 is suspended between two end bars 13 and 14, L shaped in cross section.

The supporting frame of the bed consists of two jointed longitudinal members 15, 65 pivoted at each of their extremities to leg members 16. Pivoted to each of the longitudinal members as shown at 17 is a cross brace 18, which is detachably connected to the opposite longitudinal member as 70 shown in Fig. 4. The end of cross brace 18 is bifurcated. The two sides of the bifurcation are turned in opposite directions at right angles forming a T shaped head 19 on the free ends of the cross braces 18 as shown 75 at 19. A socket 20 is formed on the opposite longitudinal member and is adapted to receive this T shaped head 19 which is securely locked therein by means of a pivoted button 21, which may be turned to prevent 80 its removal.

Cross brace 18 serves to brace the bed against side sway and also to hold the supporting frame upright while the spring structure 10 is being put in place. 85

Leg members 16 are L shaped in cross section. At their upper extremities one leg of the L is allowed to project beyond the other and is turned to form a hook 22. These projecting hooks 22 are adapted to pass through 90 openings 23, formed in end members 13 and 14, and hook over the edges thereof. Diagonal braces 24 are pivoted to end members 13 and 14 opposite openings 23 in such a manner as to cause their upper extremities 95 to engage the leg members 16, when said diagonal braces are turned at right angles to the end members 13 and 14, as is clearly indicated in Fig. 3, thus preventing the hooks 22 from becoming disengaged while 100 the bed is extended.

This simple method of locking the end members 16 to the leg members 13 and 14, without the use of screws, clamps, wedges, etc., is believed to be new and novel and is 105 one of the features of the invention.

The lower extremities of the diagonal braces 24 are provided with projections 25, which engage in openings in the upper faces of the longitudinal members 15. 110

Longitudinal members 15 are U shaped in cross section, the open face of the U pointing downward, and are each formed of two sections pivoted together. The inner extremity of one section carries a pivot pin 26 which engages in a slotted opening 27 formed on the inner extremity of the connecting section. The section carrying the slotted opening fits within its connecting section so that the two can be telescoped within the limits of the slotted opening 27.

Mounted on one of the sections, and pivoted thereto, is a lever arm 28, provided with a hand hold 29 at its longer extremity and with a pivoted link 30 at its shorter extremity. The link 30 is provided with a notch 31 at its free end, which is adapted to engage a stud 32, fixed in the opposite section of the longitudinal member 15 to that carrying the lever arm 28. An opening 33 is formed in the top of each of the longitudinal members 15 and is adapted to be engaged by the extremity of the handle 29.

When collapsed, ready for transporting, the two longitudinal members 15 are folded, as indicated in Fig. 8, with the leg members 16 folded within and the cross brace 18 folded thereon. Lever arm 28 with link 30 folded back thereon lies parallel with the longitudinal members 15, the free end thereof engaging the opening 33. The spring structure 10, with the diagonal braces 24 folded within the L shaped end members 14 and 13, is wrapped around the two folded longitudinal members 15, the whole forming a compact bundle.

The bed is erected as follows. The two sections of the longitudinal members 15 are slid upon one another until the pivot pin 26 occupies the outer end of the slot 27. The sections can then be revolved about the pivot pin 26 to their extended position, when the sections are again slid so that the pivot pin 26 occupies the opposite end of the slot 27, thus foreshortening the longitudinal members 15. The leg members 16 are turned at right angles to the longitudinal members 15 and the cross braces 18 connected. The frame is now self supporting. End bars 13 and 14 are now slipped over the projecting hooks 22 of the leg members 16, and the diagonal braces 24 brought into position and

placed in openings in the longitudinal members 15. This placing of the diagonal braces 24 simultaneously locks the end members 13 and 14 to the leg members 16. 55

The placing of end bars 13 and 14 and the diagonal braces 24 is facilitated by the fact the longitudinal members 15 are foreshortened and the spring structure 10 is in a slackened or loose condition. 60

The longitudinal members 15 are now in the position as shown in Fig. 5. Levers 28 are now opened to the position shown (Fig. 65 5) and the links 30 connected to the studs 32. The levers 28 are then forced back to their original positions, thereby lengthening the longitudinal members 15, from the broken line positions shown in Figs. 6 and 7 70 to the solid line positions in the same views. This lengthening of the longitudinal members 15 stretches the spring structure taut and ready for use. Link 30 is provided with a raised portion 34 in order to allow the 75 link to pass over the pivot pin in the lever 28.

Having thus described my invention, what I claim and desire to secure by Letters Patent is:

1. A collapsible bed comprising end members; a flexible spring structure connecting said end members; leg members provided with hook shaped upper extremities, said extremities adapted to pass through openings in said end members; diagonal braces pivoted to said end members and adapted when extended to engage said extremities and lock same in place and longitudinal members pivoted to and separating said leg members. 80 85

2. A collapsible bed comprising end members supporting a flexible spring structure; leg members adapted to detachably engage said end members; extendable longitudinal members pivoted to and separating said leg members; diagonal braces pivoted to said end members and detachably engaging said longitudinal members; cross braces pivoted to each of said longitudinal members and detachably engaging the opposite longitudinal member and means for extending said longitudinal member for the purpose of tightening said spring structure. 95 100

In testimony whereof I affix my signature. 105
FRANK M. STOLL.
